UNITED STATES PATENT OFFICE.

CHARLES H. TOMLINSON, OF MANSFIELD, OHIO.

CAR, AIR, AND ELECTRIC COUPLING.

1,319,311.

Specification of Letters Patent. Patented Oct. 21, 1919.

Application filed July 5, 1917, Serial No. 178,738. Renewed March 11, 1919. Serial No. 282,052.

To all whom it may concern:

Be it known that I, CHARLES H. TOMLINSON, a citizen of the United States, residing at Mansfield, in the county of Richland and 5 State of Ohio, have invented certain new and useful Improvements in Car, Air, and Electric Couplings, of which the following is a specification.

This invention relates to a mechanical 10 coupler which makes connections at the face of adjacent couplers for completing air and electrical connections therethrough.

The object of the invention is to provide a coupler of this kind in which the electric 15 and air connections, as well as the mechanical coupling between the cars can be operated for connecting or disconnecting cars from the outside thereof, or that the same connections can be made and broken by an 20 operator within one of the cars.

The invention consists in the novel construction, combination and arrangement of the parts.

In the accompanying drawings—

25 Figure 1 is a plan view of two couplers on adjacent car ends together with the operating means therefor.

Fig. 2 is a plan view of one of the couplers.

30 Fig. 3 is a front view of one of the couplers.

Fig. 4 is a side view partly in section of one of the couplers.

35 Fig. 5 is a horizontal sectional view of one of the couplers; and

Fig. 6 is another sectional view of one of the couplers.

The present invention is similar in many respects to applicant's co-pending application, Serial No. 175,087, but differs from it in the construction of the mechanical coupler and the operating means therefor.

40 In each coupler there is a drawbar 1 pivoted at some distance from the end of a car to be connected, having a mechanical coupler head 2 at its outer end with a contact face 3 with a gasket 4 set in the edge of the top and sides of the face to exclude water and dirt when two coupler faces are 45 abutting.

Extending from one side of each coupler 50 is a coupling pin 5 beveled at its outer end and having a locking notch 6 in one side thereof, and at the other side of the coupler 55 is a recess 7 for receiving a corresponding pin 5 of an adjacent coupler with a beveled

edge 8 to assist in guiding and alining the adjacent couplers as they are brought together. Protruding from the face of each coupler are train line pipe connections 9 and 60 10 each pressed outwardly by a spring 11 which causes these pipe connections to make a fluid-tight joint with similar connections of the adjacent coupler. Also protruding from the face of the coupler is a combined 65 air and electric connector 12 which is joined to a controlling pipe line 13 and to an electrical conductor 14. Also carried by each coupler and projecting from the face thereof are a plurality of electrical connectors 15 70 and 16 for completing the electrical controlling and service circuits between the cars. One of these contacts, as 16, may be a bus line conductor.

Extending from each coupler are pipe 75 lines 17 and 18 which are each provided with a valve 19 to control the connection through adjacent couplers, and connected to the valves 19 is a control switch 20 having a rotatable drum 21 for making and breaking 80 electrical connections, the conductors 22 of which are led to the switch through conduits 23 from the various contacts. The rotation of the drum 21 makes or breaks the electrical connections and simultaneously 85 opens or closes the valves 19 of the pipe lines. An operating lever 24 is connected to the switch having a handle 25 extending toward and operable from the side of the car, and also connected to the lever by means 90 of a link is a rod 27 of a piston movable in one direction in a cylinder 28 by fluid under pressure admitted from a pipe line 29, and movable in the other direction by fluid under pressure from a pipe line 30 connected 95 to a suitable source of pressure supply and controlled by an electropneumatic device 31 to which the conductor 14 is connected.

In each coupler head just within the opening 7 is a latch 32 adapted to engage the 100 locking notch 6 of the coupling pin 5 of the adjacent coupler. This latch is mounted on a shaft 33 and has an extending arm 34 by which it is rotatable to disengage the latch 32 from the coupling pin. A projection 35 is 105 provided for limiting the movement in the outer direction, and connected to the arm is a rod 36 surrounded by a spring 37 in a casing 38 which tends to hold the latch 32 in engaging position. A coupling pin may 110 be inserted within the coupler head, the latch merely being moved aside against the tension

of spring 37 until the locking notch is uncovered, whereupon the latch is swung into engagement therewith. In order however to move the latch for uncoupling, the outer 5 end of arm 34 is provided with a link 39 which may be grasped by an operator between the cars, or the arm may be moved by a pneumatic device comprising a rod 40 attached to a piston 41 which is movable in 10 a cylinder 42 having one end thereof connected in series with the controlling pipe line 13. As this pipe line 13 is connected through adjacent couplers by means of the combined air and electric connection 12, the admission 15 of fluid under pressure to one of the pipe lines 13 will operate the pneumatic uncoupling devices of both couplers. Therefore, the pipe lines 13 and 29 are connected together through a valve 43 to a pipe line 20 44 from a suitable source of pressure supply in each car so that upon the opening of this valve, the uncoupling cylinders 42 are energized, and at the same time the switch 20 is opened and the valves 19 connected thereto, 25 are closed.

Each electric conductor 14 may be connected by means of a two-way switch 45 either with a ground connection 46, or with a suitable source of supply 47. Normally the 30 switch in each car is connected to the ground so that when two adjacent cars are coupled the movement of the switch 45 in either car to make connection with the conductor 47 will energize both electro-responsive devices 35 31 in the two cars.

In operating couplers of this type it is necessary only to bring the coupler faces together, whereupon the coupling pins will both align the couplers for the proper connection of the air and electric connectors protruding from the face thereof and will complete the mechanical coupling of the cars by the engagement of latches 32. The air line and electric connections are not made 40 45 until the switches 20 in both cars are operated manually either from without the cars, or by an operator in one of the cars, since the combined air and electric connection provides means for operating the switch in both 50 directions from either one of the cars. To uncouple the cars it is necessary only to operate the valve 43 in one of the cars, whereupon they may be moved apart, as previously set forth.

55 I claim:—

1. The combination with a pair of self aligning couplers each having a flat outer abutting face with a projecting notched alining pin and recess and a pivoted locking latch within the recess, of separate air, 60 electric, and a combined air and electric means projecting from the face of each coupler a fluid pressure device for operating said locking latch, an electric switch remote from the coupler for making and

breaking circuits therethrough, and fluid pressure valves connected to said switch and operated therewith for opening and closing the air lines to said device and through the couplers. 70

2. A coupler having a locking pin with an alining extremity with a bevel edged opening for receiving a corresponding pin, the pin being formed with a locking notch, a latch pivoted within the opening and axially rotatable to engage in the notch of a coöperating coupler pin, an arm for operating the latch, and a pneumatic device comprising a piston and cylinder for operating the lever to release the latch. 75 80

3. In a car coupler, an alining pin with a locking notch, an opening for receiving a pin of a coöperating coupler, fluid pressure connecting means projecting from the face of each coupler and connected upon impact with an adjacent coupler, a latch in each coupler for lateral rotation to engage the pin of the coöperating coupler, a fluid pressure device comprising a piston and cylinder for operating the latch, and a pipe line 90 extending from the fluid pressure connection in the face of the coupler to the said cylinder for operating the fluid pressure devices of adjacent couplers simultaneously from either car. 95

4. In a coupler, a projecting alining and locking pin and a spaced recess, a pipe line connection extending from the outer flat abutting face of the coupler, a pivoted locking latch for engaging the pin of a coöperating coupler inserted through said recess at the side of said pin and rotatable laterally to engage the notch of the pin, an operating arm for said latch, a spring tending to hold the latch in engaging position, a fluid pressure device connected at one end in series with the pipe line through the face of the coupler and comprising a plunger to engage the arm and move it outwardly against the said spring. 100 105 110

5. In a coupler, an alining coupling pin and a recess in the face of the coupler, a pipe line connection extending from the face of the coupler, a pivoted locking latch for the pin of a coöperating coupler, an arm for operating the latch, a spring tending to hold the arm and the latch in locking position, a fluid pressure device within the coupler connected with the projecting pipe line connection for moving the arm against the 115 pressure of said spring, and a manually engageable link at the end of the arm for operating it and the latch externally of the coupler. 120

6. The combination with a pair of couplers each having a notched coupling pin and an alining recess, of an air line connection projecting from the face of each coupler and making a fluid-tight connection between the couplers when they are me- 125 130

- chanically connected, a locking latch behind the recess of each coupler for engaging the notch in the coupling pin, a spring-pressed arm tending to hold the latch in locking position, a fluid pressure device connected in series with the pipe line connection for moving the latch out of locking position, and a manually operable valve in the pipe line for admitting fluid under pressure to the said fluid pressure devices of both couplers for operating them simultaneously to release the locking latches.
5. The combination with a pair of self-aligning couplers each comprising a notched pin and recess and a pivoted locking latch, of separate air, electric, and a combined air and electric means projecting from the face of each coupler, an electric switch remote from the coupler for making and breaking circuits therethrough, fluid pressure valves connected to the switch and operated therewith for opening and closing the air lines through the coupler, means for operating the switch and said valves in both directions through the said combined air and electric connection, and a fluid pressure device for said locking latch comprising a piston, and a cylinder connected in series with the air line of the combined air
- 10 and electric connection for operating the latches of connected couplers simultaneously when the switch is operated to open the electric connections.
- 15 8. A pair of counterpart couplers, each comprising a head having recesses therein, each head having a notched pin adapted to engage the recess in the other head, a locking latch for each pin, a spring normally holding each latch in locking position, and fluid operable means connected with the latches for moving the latter to unlocking positions.
- 20 9. A car coupling device comprising two car ends having engaging counterpart coupling heads thereon, a notched pin attached to each head and extending into the other head, a spring-pressed latch in each head engaging the notch of the pin extending into such head, and fluid operable means connected with said latches and adapted to be controlled from either car end.
- 25 In testimony whereof I have signed my name to this specification, on this 30th day of June A. D. 1917.
- CHARLES H. TOMLINSON.
